UNITED STATES PATENT OFFICE.

EDDIE BELL AND ROBERT E. MENTEER, OF FREDERICK, KANSAS.

HORSE-RELEASER.

1,032,981.

Specification of Letters Patent. Patented July 16, 1912.

Application filed January 18, 1912. Serial No. 671,975.

To all whom it may concern:

Be it known that we, EDDIE BELL and ROBERT E. MENTEER, citizens of the United States, residing at Frederick, in the county 5 of Rice, State of Kansas, have invented certain new and useful Improvements in Horse-Releaseers; and we do hereby declare the following to be a full, clear, and exact description of the invention, such as will 10 enable others skilled in the art to which it appertains to make and use the same.

This invention relates to horse releasers of that general class consisting of shaft securing axle clips designed to open and drop 15 from the axle upon the draft animal becoming unmanageable.

An object of the present invention is to provide an axle clip formed of two hinged sections the legs of which are connected by 20 an H-shaped bridge piece, which pivotally secures a combined anti-rattler and trigger controlling spring this construction forming a simpler and more effective emergency clip than ordinary devices of this character.

25 A second object of the invention is to provide a novel trigger which is pivotally attached to the spring through the instrumentality of a pair of pivoted links, the trigger having a locking tongue adapted to 30 be selectively engaged in one of a series of openings formed in the free section of the hinge clip and yieldingly hold the free section in operative engagement with said H-shaped bridge piece, whereby a more positive locking together of the parts is obtained and accidental opening of the clip 35 positively prevented.

With the above objects in view the invention consists of certain novel details of construction and combination of parts herein- 40 after fully described and claimed, it being understood that various modifications may be made in the minor details of construction within the scope of the appended 45 claims.

In the accompanying drawings forming part of this specification:—Figure 1 is a fragmentary side elevation of a vehicle showing the application of our device to 50 the front axle thereof. Fig. 2 is a longitudinal sectional view through the device. Fig. 3 is a side elevation of the device showing the same in operative position in full lines and in released position in dotted lines. 55 Fig. 4 is a cross sectional view taken on the line 4—4 Fig. 2. Fig. 5 is a fragmen-

tary plan view of the device in operative position.

Referring now to the drawings in which like characters of reference designate similar parts, 10 designates the axle and 11 the axle tree. The device embodied in our invention comprises a clip formed of two sections 12 and 13 which are pivotally connected together as at 14 at substantially 60 the center of the clip, and upon the section 12 is formed a pair of ears 15 for the reception therebetween of the thill iron 16, there being the usual pin 17 engaged 65 through these ears and thill iron.

A substantially H-shaped bridge piece 18 connects the terminals of the clip sections, said terminals fitting in the indentations in the end edges of the bridge piece, and a rivet 19 or similar connector is passed 70 through the bridge piece and the terminal of the section 12 to rigidly secure the latter to the bridge piece. The free section 13 fits loosely in the related indentation of the bridge piece and is provided on the outer 75 face with a series of notches 20 the purpose of which will presently appear.

A curvilinear spring 21 is provided approximately centrally with spaced ears 22 which fit in the indentation of the bridge 80 piece nearest to the fixed section of the clip, and a pivot pin 23 is passed through the ears and bridge piece to pivotally secure the spring to the latter. The spring extends upwardly between the ears 15 and is terminally 85 bent to overlie the pin 17 as shown at 24, a lip 25 being formed on the edge of the bent portion and bearing against the head of the pin to hold the latter against escape. The lower end of the spring is bent to form an 90 eye 26, and arranged on opposite sides of the eye are spaced links 27, a pivot pin 28 being passed through the front ends of the links and through the eye.

The links extend rearwardly beyond the 100 terminal of the free section 13 and bear within recesses 29 formed in the outer edges of the H-shaped bridge piece. An upstanding trigger 30 is interposed between the rear ends of the links and a pivot pin 31 is passed 105 through the links and trigger. A locking tongue 32 is formed on the inner edge of the trigger and is adapted to be selectively engaged in one of the series of notches 20 formed in the outer face of the free sec- 110 tions 13.

By now referring to Fig. 2 it will be seen

that when the links are swung to the position shown in full lines and the trigger tongue engaged in the notch in the free section, the spring 21 will be simultaneously 5 rocked on its pivot and placed under tension, and will in this condition bear forcibly upon the thill iron 16 whereby to hold the latter against rattling, and will also hold the trigger firmly in operative position. Thus 10 it will be seen that the spring performs the dual function of an anti-rattler and a controlling spring for the trigger.

It will be understood that there are two 15 of these devices attached to the axle, and in order that they may be simultaneously operated to release the thills, a rock shaft 33 is secured to the rear side of the axle through the instrumentality of axle clips 34 having bridge pieces 35 which are provided with 20 rearward extensions having spiral terminals 37 which embrace the rock shaft. The latter is provided with upstanding cranks 38 the terminals of which normally fit in between the free end of the trigger and free 25 section of the clip. Projections 39 are arranged upon the rock shaft near the side of the vehicle box and upon depression of either projection, the shaft will be rocked and the cranks moved so as to pry rearwardly 30 the triggers whereupon the parts will assume the position shown in dotted lines in Fig. 3 and permit of the thills escaping from the vehicle.

What is claimed, is:—

35 1. A horse releaser including a clip formed

of a pair of hinged sections, a substantially H-shaped bridge piece receiving the terminals of said sections in the indentations of the end edges, one of said terminals being fixedly secured to said bridge piece, and 40 means for detachably securing the free terminal to said bridge piece comprising a spring connected to said bridge piece, a trigger having a locking tongue adapted to seat in a notch formed in the free terminal, and 45 a link pivotally connected to said spring and to said trigger.

2. A horse releaser including a clip formed of a pair of hinged sections, a bridge piece connecting the terminals of the sections, one 50 of said terminals being fixedly secured to said bridge piece and having a pair of laterally extending hinge ears adapted to receive a thill iron, the free section being provided on the outer face with a notch, a 55 spring pivotally secured to said bridge piece and extending upwardly between said hinge ears, and extending below said bridge piece, an upstanding trigger having a locking tongue adapted to seat in said notch, and a 60 link pivotally secured to said spring below said bridge piece and pivotally secured to said trigger.

In testimony whereof, we affix our signatures in presence of two witnesses.

EDDIE BELL.

ROBERT E. MENTEEER.
